BARBER'S SHINGLING CLIPPER

Douglas Adams, Menard, Ill.

Application April 26, 1939, Serial No. 270,245

3 Claims. (Cl. 30—212)

My invention relates to new and useful improvements in hair clippers.

An important object of my invention is the provision of a hair clipper that has two cutting edges to facilitate the cutting of the hair.

Another object of my invention is the provision of a hair clipper having means integral therewith to cooperate with the cutting blades and to perform the same function as the comb ordinarily employed by a barber.

Still another object of my invention is the provision of a hair clipper that is simple in construction, efficient in operation and inexpensive to manufacture.

Other objects and advantages of my invention will be apparent during the course of the following description.

In the drawing, forming a part of this specification, and in which like numerals are employed to designate like parts throughout the same:

Figure 1 is a top plan view of a device embodying my invention.

Figure 2 is a vertical sectional view, taken on the line 2—2 of Figure 1.

Figure 3 is a longitudinal sectional view, taken on the line 3—3 of Figure 1.

Figure 4 is a vertical sectional view, taken on the line 4—4 of Figure 1, and

Figure 5 is a transverse sectional view, taken on the line 5—5 of Figure 3.

In the accompanying drawing, wherein for the purpose of illustration, is shown a preferred embodiment of my invention, the numeral 10 designates a lower cutting blade of substantially rectangular formation in plan and including a central longitudinal web 11 which is formed with a plurality of spaced teeth 12 extending laterally therefrom and on either side thereof. The teeth 12 terminate a substantial distance from the rear portion 13 of the web 11 but extend flush with the forward end 14 thereof. The teeth 12 are of substantially triangular formation in side elevation having an upwardly sloping bottom edge 15 and a horizontal upper edge 16 which join to form a rounded point 17. The upper edge 16 is provided adjacent the web 11 with a recess 18. In cross section the extremities of the teeth 12 are formed with a rounded bottom part having upwardly divergent sides and an oval top portion which merge into the rounded points 17 in a manner whereby no sharp or rough edges are evidenced. The horizontal face of the recess 18 is flat and the juncture thereof with the side walls of the tooth form a sharp cutting edge.

The upper cutting blade 19 is substantially shorter than the lower blade 10, and is similarly formed with an elongated central web 20 having spaced teeth 21 extending laterally therefrom on either side thereof. The teeth 21 are adapted to register with the teeth 12 in the lower blade 10 and to be received within the recesses 18. The teeth 21 are of substantially paraboloidal formation in cross section and are provided with a flat bottom face 22 adapted to have a close fitting sliding engagement with the horizontal faces of the recesses 18. The posts 23 and 24 are threadedly carried by the web 11 of the lower blade 10 and extend vertically therefrom to be received by the elongated slots 24' and 25 in the upper blade 19.

The handle member 26 is formed with an angularly extending thumb support 27 and has the inner end thereof bent inwardly and downwardly as at 28 to terminate in a forwardly extending shank 29 which is bolted, or otherwise secured, to the rearward portion 13 of the lower blade 10. The tubular member 30 is integrally formed on the handle member 26 and in the same longitudinal plane as the shank 29 but elevated with respect thereto to lie in a horizontal plane above the upper blade 19. The tubular member 30 is provided with a transverse inner closure wall 31 and an open outer end which is externally screw threaded to receive the cap 32. The actuating rod 33 is formed with a laterally extending shank 35 which is pivotally received by the rear portion of the upper blade 19, and a screw threaded bore 34 which receives the adjusting screw 36. The screw 36 extends rearwardly thereof through the end closure wall 31 of the tubular member 30, and has the head 37 thereof positioned within the tubular member adjacent the end cap 32. A coil spring 38 is interposed between the head 37 of the adjusting screw and the inner closure wall 31 of the tubular member to hold the actuating rod 33 and consequently the upper blade 19 in a fully retracted position.

The companion handle member 39 is formed with a finger ring 40 intermediate its ends, and the inner end 41 thereof is bent angularly inwardly as at 42, terminating in bifurcations 43 and 44 which embrace and are secured to the rearward end of the actuating rod 33 by the set screw 45. Bifurcations 46 and 47 are formed on the tubular member 30 and extend laterally and forwardly thereof to embrace the handle member 39 at the juncture thereof with the angularly bent portion 42 and effect a pivotal engagement therewith by means of the bolt 48. The cover

plate 49 is positioned above the central web 20 of the upper blade 19 and is formed with longitudinal flanges 50 and 51 which engage the web at its point of junction with the teeth 21. The posts 23 and 24 extend upwardly through the cover 49 and the thumb screws 52 and 53 are threaded thereon to engage the top surface of the cover. The vertical flanges 50 and 51 of the cover support the same in superimposed relation with the upper blade 19 and will impart a substantial resilient action to the cover in a manner whereby the thumb screws 52 and 53 may be adjusted to vary the degree of frictional engagement between the upper and lower blades 19 and 10. It may be seen that the resilient nature of the cover imparted thereto by virtue of the longitudinal flanges 50 and 51 will prevent a binding from being effected between the jaws but will permit a sliding frictional engagement between the cutting faces of the upper and lower teeth of the blades.

As hereinbefore described, the upper blade 19 is held in a retracted position under the resilient action of the coil spring 38, and it may be seen that upon manual actuation of the handle members 26 and 39, a reciprocating motion will be imparted to the actuating rod 33 which will reciprocally actuate the upper blade within the limits of the elongated slots 24 and 25. The extremities of the lower teeth 12 comprise comb teeth, and inasmuch as they extend laterally on either side of the lower web 11, the device in its entirety may be moved either upwardly or downwardly on the scalp. The ends 17 of the teeth are blunted to prevent the same from breaking or cutting the scalp. In moving the device either upwardly or downwardly the groups of hair will be engaged between the ends of the comb teeth in advance of the line of cut, and will split fan-like into the inner portion of the teeth where a reciprocating movement of the upper blade 19 will sever the same. It may thus be seen that the ends of the lower teeth 12 will automatically perform the function which is ordinarily performed by the comb that the barber carries in advance of the shear or clipper.

The present invention is particularly adapted to produce the shingling cut, but it is to be understood that it will perform equally well in cutting the hair regardless of the type of cut desired.

It is to be understood that the form of my invention, herewith shown and described, is to be taken as a preferred example of the same, and that various changes in the size, shape and arrangement of parts may be resorted to without departing from the spirit of my invention, or the scope of the appended claims.

Having thus described my invention, I claim:

1. In a hair clipper of the type having a lower blade formed with a plurality of spaced teeth projecting laterally from the sides thereof and an upper blade slidably mounted on the said lower blade and being formed with spaced laterally projecting teeth adapted to cooperate with the teeth of the said lower blade in the cutting of hair; means to reciprocally actuate the upper blade relative to the said lower blade comprising a handle member secured to the said lower blade, and having a tubular element formed thereon in alignment with the longitudinal axis of the said upper and lower blades, the end of the tubular element confronting the upper blade being provided with a closure wall; an actuating rod pivoted to the said upper blade; a handle member

pivotedly carried by the said first-mentioned handle member and having a part pivotally connected to the said actuating rod; a rearwardly extending headed shank screw-threadedly carried by the said actuating rod and extending through the closure wall and into the tubular element of the said first-mentioned handle member; and spring means positioned within the tubular element intermediate the closure wall and the head of the shank, said spring means coacting with the said shank to hold same normally fully retracted therein, the said shank being adjustable to vary the tension of the said spring means to regulate the ease with which the handle member may actuate the said upper blade.

2. In a hair clipper of the type having a lower blade formed with a plurality of spaced teeth, projecting laterally from either side thereof, and an upper blade slidably mounted on the said lower blade and being formed with spaced laterally projecting teeth adapted to cooperate with the teeth of the said lower blade in the cutting of hair, means to slidably actuate the upper blade relative to the lower blade comprising a handle member secured to the said lower blade; an actuating rod pivoted to the said upper blade; a handle member pivotally carried by the said first-mentioned handle member and having a part extending beyond the above connection and pivotally connecting with the said actuating rod; and resilient means cooperating with the said first and second-mentioned handles to hold the upper blade normally retracted with respect to said lower blade subject to forward actuation by the second-mentioned handle member.

3. In a hair clipper the combination of a lower blade formed with a plurality of spaced teeth, projecting laterally from either side thereof, said teeth having inner recesses in their upper faces, the longitudinal sides of which comprise cutting edges and the ends of said teeth constituting combing members to direct the hair against the said cutting edges; an upper blade slidably mounted on the said lower blade and being formed with spaced laterally projecting teeth adapted to be received within recesses in the teeth of the lower blade and cooperating with the cutting edges thereof in the cutting of hair, a handle member secured to one end of the said lower blade, said handle member having a tubular element formed thereon in longitudinal alignment with the center of the said upper and lower blades, the end of the tubular element confronting the lower blade being provided with a closure wall; an actuating rod pivoted to the said upper blade; a handle member pivotally carried by the said first-mentioned handle member and having a part extending beyond the above pivotal connection and pivotally connecting with the said actuating rod; a longitudinally adjustable member carried by the actuating rod, which member is slidably received in the tubular element through the said closure wall; and spring means within said tubular element seated against the closure wall and a part of the adjustable member and cooperating with the said adjustable element to hold the said upper blade normally retracted, movement of the adjustable member relative to the upper blade acting to vary the tension of the spring means to regulate the ease with which the upper blade may be moved relative to the lower blade.

DOUGLAS ADAMS.
